UNITED STATES PATENT OFFICE

JOSEPH C. LEO, OF OELWEIN, IOWA

DESIGN FOR A DANGER SIGNAL LIGHT CASING

Application filed October 2, 1931. Serial No. 41,289. Term of patent 14 years.

To all whom it may concern:

Be it known that, JOSEPH C. LEO, a citizen of the United States of America, residing at Oelwein, in the county of Fayette and State of Iowa, has invented a new, original, and ornamental Design for a Danger Signal Light Casing, of which the following is a specification, reference being had to the accompanying drawings, forming part thereof.

Figure 1 is a front elevation of the signaling device shown in operating position,

Figure 2 is a top plan view, and Figure 3 is a side elevation of Figure 1, both shown on a reduced scale.

I claim:

The ornamental design for a danger signal light casing, as shown.

In testimony whereof I affix my signature.

JOSEPH C. LEO.
